UNITED STATES PATENT OFFICE.

MILTON H. SHOENBERG AND LESTER SCHON, OF SAN FRANCISCO, CALIFORNIA; SAID SCHON ASSIGNOR TO SAID SHOENBERG.

DESIGN FOR A COMBINED CONVECTION AND RADIANT HEATER.

Application filed April 30, 1924. Serial No. 9,438. Term of patent 14 years.

To all whom it may concern:

Be it known that we, MILTON H. SHOENBERG and LESTER SCHON, both citizens of the United States, residing in the city and county of San Francisco, State of California, have invented a new, original, and ornamental Design for a Combined Convection and Radiant Heater, of which the following is a specification, reference being had to the accompanying drawing, forming part thereof.

The figure is a view of the combined convection and radiant heater, showing our new design.

We claim:

The ornamental design for a combined convection and radiant heater as shown.

Dated: April 16th, 1924, San Francisco, California.

MILTON H. SHOENBERG.
LESTER SCHON.
